United States Patent Office

Des. 225,793
Patented Jan. 9, 1973

225,793

HAT

Joseph M. Aquila, 1671 Burgess Road,
Cleveland, Ohio 44112

Filed Jan. 20, 1971, Ser. No. 108,252

Term of patent 14 years

Int. Cl. D2—03

U.S. Cl. D2—258

Fig. 1

Fig. 2

Fig. 3

Fig. 4

FIG. 1 is a perspective view of a hat embodying my new design;

FIG. 2 is a side elevational view thereof;

FIG. 3 is a front elevational view thereof; and

FIG. 4 is a plan view thereof.

The other side view is substantially identical to the side shown in FIG. 2, and the rear view is substantially identical to the front view shown in FIG. 3.

I claim:

The ornamental design for a hat, as shown and described.
